UNITED STATES PATENT OFFICE.

CHARLES C. SPREEN, OF DETROIT, MICHIGAN, ASSIGNOR TO KELVINATOR CORPORATION, OF DETROIT, MICHIGAN, A CORPORATION OF MICHIGAN.

MECHANICAL REFRIGERATION.

Application filed November 5, 1925. Serial No. 63,932.

My invention relates to mechanical refrigeration and the principal object of my invention is to provide new and improved apparatus for this purpose. In the drawings accompanying this specification and forming a part thereof I have shown, for purposes of illustration, one form which my invention may assume. In these drawings:

Figure 1 is a front elevation of this illustrative embodiment of my invention,

Figure 2 is a section on the line 2—2 of Figures 1, 3, and 4,

Figure 3 is a section on the line 3—3 of Figure 2,

Figure 4 is a rear elevation, while

Figure 5 is a section on the line 5—5 of Figure 4.

The device shown herein comprises a cabinet 160 having a front wall 174, side walls 169 and 170, a rear wall 171, a top 26, and a partition 175 separating the lowest portion of the cabinet 160 into a compressor chamber 163 and an extension 161 of a main refrigerated chamber 162 also divided from the compressor chamber 163 by the partition 175. The front wall 174 is provided with an aperture 30 extending substantially the entire height of the main refrigerated compartment 162 and closed by a door 31 and with an aperture 32 extending substantially the entire height of the extension refrigerated compartment 161 and closed by a door 176.

Disposed across the top of the refrigerated chamber 162 is a refrigerating apparatus 34 consisting of a brine tank 35 containing the usual expansion coil (not shown), an expansion valve 36 controlling the flow of compressed refrigerant into the expansion coil, and a thermostat 39 positioned within the end turns 40 of the expansion coil. The brine tank 35 is supported in the refrigerated chamber 162 by means of a pair of straps 41 each secured at its upper end 42 to the cabinet top 26 and at its lower end 43 to the cabinet rear wall 171, and each formed intermediate its ends to embrace the brine tank 35. The expansion valve 36 is supported in part by the duct 44 connecting it with the expansion coil and partly by the duct 177 leading to the expansion valve 36 from the condenser, while the expansion coil end turns 40 are supported in part by the duct 46 connecting these end turns with the main body of the expansion coil and partly

by the duct 47 leading from the expansion coil end turns 40 to the intake of the compressor.

Disposed about the refrigerating apparatus 34 is a shield 48 having one edge 49 abutting the side wall 169, having the opposite edge 50 extending upwardly almost to the top of the refrigerated compartment 162 and disposed adjacent to but spaced from the other side wall 170, having a rear edge 51 spaced from the rear wall 171 and slightly upturned, having a front portion 52 extending upwardly in front of the refrigerating apparatus 34 to the cabinet top 26 and secured to forwardly projecting offsets 53 in the straps 41 and provided with an aperture 54 affording access therethrough to the ice pans 55 disposed in the central aperture 56 in the brine tank 35, and having a base portion 57 connecting the four edge portions 49, 50, 51, and 52, secured to downwardly projecting offsets 58 in the straps 41, and sloping downwardly to a central depression communicating with a drain duct 59.

The refrigerant return duct 47, the wires 60 from the switch 38, and the drain duct 59, all enter the upper end of a sheath 61 and pass within this sheath through the refrigerated chamber 162 and partition 175 into the compressor compartment 163 where the refrigerant return duct 47 is connected to the inlet 178 of a compressor 164 connected by means of a duct 190 to the other end of the condenser, the wires 60 extend to the motor 165 connected to the compressor 164 by means of a belt 166, and the drain duct 59 extends on through the bottom of the cabinet 160. In this embodiment of my invention the motor 165 and compressor 164 are mounted upon a common base 167 slidably mounted upon guide-ways 168 carried by the lower ends of the side walls 169 and 170 of the cabinet 160, the cabinet sides 169 and 170 are extended rearwardly beyond the cabinet rear wall 171 to provide a flue 172 extending up the back of the cabinet 160 in free communication with both the compressor chamber 163 and the space above the cabinet 160, and the condenser coil 173 is positioned within this flue 172.

It will be apparent to those skilled in the art that in the embodiment of my invention herein disclosed the various portions of the apparatus are located in a single unitary cabinet and mounted in a manner to secure

maximum utilization of space and at the same time satisfactory operating efficiency, the shield positioned about the brine tank serves not only as a drip pan to collect condensate but also to induce and assist circulation of the air between the space about the refrigerating apparatus and the space beneath the shield, the embodiment of my invention provides an extremely simple form 10 of refrigerating apparatus which can be manufactured at a minimum cost and maintained in operation with a minimum of expense, the use of the sheath to house the various pipes and wires as they pass through the 15 refrigerating chamber assists in holding these parts in position and in maintaining the refrigerated chamber clean, the construction of a single member to serve as a drip pan and to induce circulation permits the 20 omission of one part heretofore necessary, the provision of the shield front plate permits the formation of the cabinet with a door extending the full height of the main refrigerated chamber and thus permits the 25 use of a single door for this purpose rather than the two doors heretofore customary, the projection of the side walls of the cabinet insures the spacing of the cabinet from the house wall and the formation of a flue 30 adapted to facilitate the flow of air through the compressor compartment and also provides an eminently satisfactory location for the condenser coil, the division of the lowest part of the refrigerator provides an extremely cold compartment suitable for the 35 reception and storage of those articles which must be maintained very cold, and that this division, and the positioning of the condenser coil in the flue on the back of the 40 cabinet, provide an arrangement of the compressor mechanism whereby the entire mechanism is readily accessible without withdrawing or disconnecting any part of that mechanism.

45 It will therefore be apparent to those skilled in the art that the apparatus shown herein embodies a large number of advantages over apparatus heretofore in use, both those advantages which I have specifically 50 enumerated or suggested and other advantages which I have neither enumerated nor suggested but which are nevertheless present. It will also be apparent to those skilled 55 in the art that the particular form of my invention herein shown and described may be variously changed and modified without departing from the spirit of my invention or sacrificing these advantages. It will 60 therefore be understood that this disclosure is illustrative only and that my invention is not limited thereto.

I claim:

1. A refrigerator cabinet comprising lateral wall means and top wall means and partition means defining together a machinery compartment across the rear of the lower portion of said cabinet and a refrigerating compartment in the upper portion of said cabinet and a refrigerated compartment between said refrigerating compartment and 65 said machinery compartment and also across the front of the lower portion of said cabinet in front of said machinery compartment, refrigerating mechanism disposed in said machinery compartment, refrigerating apparatus disposed in said refrigerating compartment and operatively connected to said refrigerating mechanism, and a door in said lateral wall means affording access to said refrigerated compartment. 70 80

2. A refrigerator cabinet comprising lateral wall means and top wall means and partition means defining together a machinery compartment across the rear of the lower portion of said cabinet and a refrigerating compartment across the entire upper portion of said cabinet and a refrigerated compartment between said refrigerating compartment and said machinery compartment and also across the front of the lower portion of 90 said cabinet in front of said machinery compartment, refrigerating mechanism disposed in said machinery compartment, refrigerating apparatus disposed in said refrigerating compartment and operatively 95 connected to said refrigerating mechanism, and a door in said lateral wall means affording access to said refrigerated compartment. 100

3. A refrigerator cabinet comprising lateral wall means and top wall means and partition means defining together a machinery compartment across the rear of the lower portion of said cabinet and a refrigerating compartment across the entire upper portion of said cabinet and a refrigerated compartment between said refrigerating compartment and said machinery compartment and also across the front of the lower portion of said cabinet in front of said machinery compartment, refrigerating mechanism disposed in said machinery compartment, refrigerating apparatus disposed in said refrigerating compartment and operatively connected to said refrigerating mechanism, and a door in said lateral wall means affording access to both said refrigerating compartment and said refrigerated compartment. 110 115

In testimony whereof I hereunto affix my signature.

CHARLES C. SPREEN.
